P. A. BEYER

WINDOW

Filed July 18, 1927

UNITED STATES PATENT OFFICE.

PAUL ALFRED BEYER, OF DETROIT, MICHIGAN.

WINDOW.

Application filed July 18, 1927. Serial No. 206,641.

The invention primarily has for its object to provide certain new and useful improvements in window construction wherein the sashes are individually slideable in the usual manner and in which means is provided to permit the sashes to swing inwardly from one edge to render the outside thereof readily accessible for cleaning purposes, or for glazing and painting.

10 The invention further resides in the provision of novel hinge devices at one side of the window casing and novel removable sash guide and parting strip members which cooperate in properly guiding the sashes in ordinary use or for permitting the inward hinge movement thereof when desired, and means to move said guides and strip.

20 A further object of the invention is to provide guides for the sashes which will not be effected by damp weather to cause the sashes to stick, other means to provide for tight fitting of the sashes and against water leakage, and still further means to hold the sashes to position without the use of weights and cords.

25 The invention still further resides in the novel details of construction, combination and arrangement of parts, all of which will be first fully described, then be particularly pointed out in the appended claims, reference being had to the accompanying drawings, in which:

30 Figure 1 is a perspective view illustrating the invention.

35 Figures 2 and 3 are horizontal cross sections taken on the line 2—2 and 3—3 respectively on Figure 1.

Figure 4 is a vertical cross section taken on the line 4—4 on Figure 3.

40 Figure 5 is a vertical cross section taken on the line 5—5 on Figure 3.

Figure 6 is a fragmentary face view illustrating the action of one of the hinged hinge keepers.

45 In the drawings, in which like numerals of reference indicate like parts in all of the figures, 1 indicates the window casing sides, 2 the casing sill and 3 the top cross member thereof.

50 One casing side (the left side in this disclosure) is provided with guide beads 4 and a separator strip 5 which cooperate to form two parallel and adjacent window guide grooves, the grooveways are preferably lined with metal as at 6 to reduce to the mini-

mum possibility of the sashes sticking in damp weather.

At the other side of the casing and at the upper half thereof similar guide beads 7 are provided and cooperate with the separator strip 8 to provide the sash grooves, the said grooves also being metal lined as at 9 for the purposes hereinbefore mentioned.

55 The usual upper and lower window sashes are indicated at 10 and 11 respectively and it is to be understood that they slide vertically in the grooveways hereinbefore described and in lower continuations of the right hand grooveways, which said extensions are constructed in a peculiar manner as will hereinafter become apparent.

60 To provide for a tight fitting of the lower sash edge and to guard against water leakage, a rubber bumper strip 12 may be mounted upon the sill in position for being engaged by the sash when lowered and the outside edge of the sill may be provided with an upstanding flange to the rear of which may be provided a drain groove 14 65 from which any water collected therein may be drained through the holes 15 extending from the said groove through the front face of the sill.

65 Each of the sashes 10 and 11 is provided at the left hand edge with an upper and a lower hinge pintle 16 and 17 respectively, which are secured as at 18 to the said sashes. The pintles 16 and 17 are adapted to cooperate with upper and lower keepers 19, 90 secured as at 20 to the adjacent bead in the case of the lower sash, and to the adjacent separator strip in the case of the upper sash, in forming hinges upon which the sashes may be swung outwardly from the window casing in a manner later to be described.

70 The lower keepers 19 are fixed or rigid in construction but the upper keepers are hinged as at 21 so that the hinged portion 100 may be swung upwardly in the manner indicated in Figure 6 of the drawings for a purpose later to be described, suitable recesses 22 being provided on the bead and separator strip to permit this movement of the hinged portions of the keepers. The said hinged portions are hinged "off balance" so that they will always tend to fall to the normal horizontal position and both sets of keepers are suitably apertured to re- 105 110

ceive the hinge pintles 16—17 when the sashes are lowered into position.

It is necessary to hinge the upper keepers to permit the lower hinge pintles 17 to pass 5 them when the sashes are raised and to remove the hinge portions of the keepers from contacting relation with the upwardly moving lower hinge pintles each sash is provided at its lower left hand corner with a cam 10 strip 23 which will engage the hinged keeper portions and raise them to a substantially vertical position out of engagement with the hinge pintles. It will be observed by reference to Figure 6 of the drawings that the 15 cam strip is long enough to permit raising of the sashes so that the lower hinge pintles may be raised a considerable distance above the upper keepers. This is particularly essential in the case of the lower sash, so that 20 the said sash may be elevated so that its lower edge will be high enough to permit the upper sash, when lowered to the outwardly hinging position, to be swung outwardly beneath the said sash. Thus the upper sash 25 may be swung outwardly on its hinge connections independently of the upper sash or both sashes may be lowered and swung outwardly on their hinge connections at the same time, if desired.

30 To form proper continuations of the right hand sash grooves and at the same time to provide for the proper freeing of the right hand sash edges to permit outward swinging of the sashes on their hinge connections, the 35 outer bead cooperative in forming the upper grooveway for the outer sash is continued down to the sill and cooperates with the thin flat metal strip 24 in forming a continuation of the grooveway which accommodates the 40 said upper sash. Other thin flat guide strips 25 and 26 are provided and are so positioned that they cooperate in forming a continuation 45 of the upper guideway for the lower sash and a suitable recess 27 is provided to receive the strip 26 when collapsed in a manner later to be described.

Each of the strips 24, 25 and 26 is provided at its lower end with a shaft extension 50 extending into a recess 29 formed in the sill and covered by a removable strip 30.

Gears 31 are fixed upon the shaft extensions of the strips 24 and 25 and another gear 32 is secured upon the shaft extension of the strip 26 and toothed bars 33 and 34 55 are provided, the former being adapted to act on both gears 31 and the latter to act on the single gear 33. Thus, by pulling outwardly on the bar 33 both strips 24 and 25 will be moved from the sash groove forming 60 position or normal position to the collapsed position relatively flat against the casing side to free the right hand edges of the sashes and permit them to swing outwardly on their hinge connections 16, 17 and 19. Similar movement of the strip 26 may be effected

by an outward movement of the toothed bar 34.

The bars 33 and 34 pass through the inside edge of the sill and are provided with handles 35 by which they may be conveniently actuated.

In the upper sash receiving grooveways flat springs 36 may be secured to engage the edges of the window sashes and secure them to elevated positions without the necessity of using more or less expensive sash weights pulley and cord equipment which are constantly getting out of order.

In the constructions I have herein described it is possible to raise and lower the window sashes in the same manner and as conveniently as is possible in the conventional form of window construction. When, however, it is desired to wash the windows, or to perform other tasks usually requiring one to climb out of the window to get at the outer faces of the sashes, it is only necessary to lower the sashes so that the pintles 16 and 17 will move into the apertures of the keepers 19 and to pull outwardly on the bars 33 and 34. The strips 24, 25 and 26 will thus be moved out of normal groove forming position to their collapsed position flat against the right hand casing side and will free the right hand edges of the sashes and permit them to be swung outwardly on their hinging connections.

If it is desired to swing the lower sash only it is only necessary to release the innermost strip 26. It will also be observed that the said innermost strip 26 operates independently while the other two strips 24 and 25 operate in unison. Thus it is unnecessary to move the strips 24 and 25 unless the upper sash is to be swung outwardly and when the upper sash is to be swung outwardly the said strips may be moved in one operation.

It is also possible to swing the upper sash outwardly without so treating the lower sash. In this case, the lower sash will be raised so that its cam plate 23 will raise the hinge portion of the upper keeper in the manner illustrated in Figure 6 of the drawing and so that the lower edge of the sash will be slightly above the upper edge of the upper sash when lowered onto the sill. The lowering of the upper sash, of course, brings its hinge pintles into hinge forming cooperation with the keepers so that when the strips 24, 25 and 26 (all have to be actuated in this case) are actuated the said sash may be swung outwardly on its hinged connection.

When the sashes are moved upwardly their cam plates 23 serve to hold the hinge portion of the keepers upwardly against any tendency to fall down beneath the hinge pintles and prevent lowering of the sashes.

From the foregoing description, taken in connection with the accompanying drawings, it is thought that the novel details of con-

struction, the manner of use and the advantages of my invention will be readily apparent to those skilled in the art to which it relates.

5. What I claim is:

1. The combination with the window frame and the vertically slidable sashes, guides for the sashes at each side of the frame, separable hinge elements carried in part by the frame and by the sashes at one side of the window, the guides at the opposite side of the window having movable sections, and gear and toothed bar devices to move the movable guide sections.

10. 2. The combination with the window frame and the vertically slidable sashes, guides for the sashes at each side of the frame, separable hinge elements carried in part by the frame and by the sashes at one side of the window, the guides at the opposite side of the window having movable sections, and means to move one movable guide section individually and other of said guide sections collectively.

15. 3. The combination with the window frame and the vertically slidable sashes, guides for the sashes at each side of the frame, separable hinge elements carried in part by the frame and by the sashes at one side of the window, the guides at the opposite side of the window having movable sections, each said movable section having a shaft extension, a gear fixed on each shaft, and longitudinally movable rack bars to engage and rotate the gears to move the movable guide sections for the purposes specified.

20. 4. The combination with the window frame and the vertically slidable sashes, guides for the sashes at each side of the frame, separable hinge elements carried in part by the frame and by the sashes at one side of the window, the guides at the opposite side of the window having movable sections, each said movable section having a shaft extension, a gear fixed on each shaft, and longitudinally movable rack bars to engage and rotate the gears to move the movable guide sections, and said frame having a recess into which the shaft extensions project and in which said rack bars are movable and slots through which said bars project to be accessible for manipulation, and a removable cover plate to cover said recess.

25. 5. In a window structure of the character stated wherein is provided the casing including a sill and sash grooves, and vertically slidable sashes; a rubber bumper strip secured upon the sill beneath the sashes for the purpose described.

30. 6. In a window structure of the character stated wherein is provided the casing including a sill and sash grooves, and vertically slidable sashes; an upstanding flange at the weather face of the sill, said sill having a water collecting groove behind the flange and water discharging holes leading from the groove through the weather face of the said sill, a rubber bumper strip secured upon the sill beneath the sashes for the purposes described.

water collecting groove behind the flange and 65 water discharging holes leading from the groove through the weather face of the said sill.

7. The combination with the window frame and the vertically slidable sashes, 70 guides for the sashes at each side of the frame, separable hinge elements carried in part by the frame and by the sashes at one side of the window, the guides at the opposite side of the window having movable sections, and means to move the movable guide sections, said separable hinge elements comprising upper and lower hinge pintles carried by each sash, and upper and lower aper- 75 tured keepers carried by the window frame in position to receive the pintles when the sashes are lowered, said upper keepers having hinged portions to permit certain of the hinge pintles to pass when the sashes are raised, and means to hold the hinged keeper portions raised until the passed hinge pintles again pass on their down travel and then permit them to fall by gravity to their normal positions, said hinged keeper portions being hinged off balance to cause them to 80 tend to fall back to their normal positions when raised.

8. The combination with the window frame and the vertically slidable sashes, 85 guides for the sashes at each side of the frame, separable hinge elements carried in part by the frame and by the sashes at one side of the window, the guides at the opposite side of the window having movable sections, and gear and toothed bar devices to 90 move the movable guide sections, said movable sections being in the nature of flat metal strips.

9. The combination with the window frame and the vertically slidable sashes, 95 guides for the sashes at each side of the frame, separable hinge elements carried in part by the frame and by the sashes at one side of the window, the guides at the opposite side of the window having movable sections, and gear and toothed bar devices to 100 move the movable guide sections, said movable sections being in the nature of flat metal strips, and said guides being metal lined for the purpose specified.

10. In a window structure of the character stated wherein is provided the casing including a sill and sash grooves, and vertically slidable sashes; an upstanding flange at the weather face of the sill, said sill having a water collecting groove behind the flange and water discharging holes leading from the groove through the weather face of the said sill, a rubber bumper strip secured upon the sill beneath the sashes for the purposes described.
